UNITED STATES PATENT OFFICE.

WILL R. SAVAGE, OF OMAHA, NEBRASKA.

ELECTRIC RADIATOR.

1,330,904.

Specification of Letters Patent. Patented Feb. 17, 1920.

Application filed April 10, 1915. Serial No. 20,561.

To all whom it may concern:

Be it known that I, WILL R. SAVAGE, a citizen of the United States, residing at Omaha, in the county of Douglas and State 5 of Nebraska, have invented certain new and useful Improvements in Electric Radiators, of which the following is a specification.

This invention relates to electric radiators.

One object is to provide an electric heating means for radiators embodying among other characteristics a double threaded winding resistance multiple series or three heat combination in such form or arrangement that a single, double or quadruple heat may 10 be established in the heating means and uniformly distributed from end to end of the radiator to heat the water uniformly in all the sections of the radiator.

Another object resides in the provision 20 of an electric radiator wherein the heating means is compact and easily applied to the radiator and easily removed therefrom if desired.

A still further object is to provide an electric heating device for radiators in which the heating means is inclosed in a tube whose 25 ends are closed and which is located in a conduit at the bottom of the radiator and at its ends supported by bushings removably connected to the end sections of the 30 radiator, one of the bushings being chambered to snugly but loosely receive the corresponding end of the tube and provided with passages to establish communication between the radiator sections and the chamber of the chambered bushing around the adjacent end of the tube with said chambered bushing provided with an opening 35 leading from its chamber so that various 40 valved devices may be interchangeably connected with the chambered bushing for different purposes.

It is still further designed to provide a heating means for electric radiators wherein 45 the parts may be easily assembled or disassembled and wherein when the parts are assembled different electrical connections may be easily and readily applied to the heating means for the purpose of operating the heating means under a single, double or quadruple heat application.

With the above and other objects in view, the present invention consists in the combination and arrangement of parts herein- 50 after more fully described, illustrated in the

accompanying drawings and particularly pointed out in the appended claims, it being understood that changes may be made in the form, proportion, size and minor details without departing from the spirit or sacrificing any of the advantages of the invention. 60

In the drawings:

Figure 1 is a longitudinal sectional view through the lower portion of a sectional 65 radiator illustrating my heating device in elevation.

Fig. 2 is a front view of a portion of a sectional radiator, partly in section illustrating a valved connection for the supply of 70 water to the radiator.

Fig. 3 is a similar view illustrating the application thereto of a valved draining device.

Fig. 4 is a front elevation of a portion of 75 a sectional radiator illustrating my improved heating device located therein and to which is also connected a gage glass.

Fig. 5 is a transverse sectional view on the line 5—5 of Fig. 1. 80

Fig. 6 is a detail view partly in longitudinal section and partly in elevation illustrating my improved heating means.

Fig. 7 is an end view of the ported bushing looking from the inside thereof, the same 85 being applied and showing the heating means.

Fig. 8 is a side elevation of the rear end of the heating element disposed within the ported bushing 27. 90

Fig. 9 is an elevation of the heating core in one condition and partly broken away, illustrating the supporting rod for the core and also showing the multiple series circuits wound thereon and connected to their terminals. 95

Fig. 10 is an end view of that part of the invention which is illustrated in Fig. 9.

Fig. 11 is a diagram of the multiple series circuits formed on the core illustrated in 100 Fig. 9.

Fig. 12 is a face view of the metallic ring which has connection with the core supporting rod at the rear end of the latter and illustrating the two rear terminals to which 105 the multiple series circuits are connected at the rear end of the heating device.

Fig. 13 is a face view of the collar 55 mounted on the end of bushing 25 and an end view of the bushing 64. 110

Fig. 14 is a detail view illustrating a form of bushing which may be substituted for the bushing 27.

Referring now more in detail to the accompanying drawings, the radiator is shown as composed of sections 20 whose lower ends have communicating passages 21 formed by the connecting nipples 22, providing a conduit adjacent the bottom of the radiator. 10 The end sections have screw threaded openings 23 and 24 disposed in alinement with said conduit.

A bushing 25 has its inner end exteriorly screw threaded, as at 26 for removable fit 15 in the aforesaid screw threaded opening 23 at one end of the radiator. A chambered exteriorly screw threaded bushing 27 has detachable connection in the screw threaded opening 24 at the opposite end of the radiator. 20 The chambered portion 31 of this bushing 27 loosely receives one end of the heating means inclosing tube 28 so that as the bushing 27 is manipulated to screw it into the screw threaded opening at the corresponding 25 end of the radiator, the chambered portion of the bushing rotates or swivels over the corresponding end of the inclosing tube 28. The end of the tube which fits in the chambered portion of the bushing 27 is closed by 30 a plug or the like 29 which is preferably screwed into the tube. This screw threaded connection between the tube and plug may be sealed by welding, soldering, or otherwise, if desired, to prevent leakage.

35 The bushing 27 is provided with a plurality of grooves 30 formed in the walls of its chamber so as to establish communication between the adjacent radiator section and the chamber 31 of the bushing 27 from 40 which chamber leads a screw threaded opening 32 formed in the head of the bushing 27. This screw threaded opening 32 is adapted to detachably receive any suitable connection for passing water through the 45 bushing by way of the passages 30 into or out of the radiator. For instance, as shown in Fig. 2 a nipple 33 is connected in the screw threaded opening 32 for the connection therewith of the valved pipe 34 of a 50 water main by means of which the radiator may be supplied with water. For this valved pipe 34 and nipple connection 33 there may be substituted, if desired, a valved drain cock connection 35 or instead 55 of either of these connections there may be removably connected in the opening 32 of the bushing 27 the lower end of a common gage glass 36 to show the height of water within the radiator. The gage glass may 60 have its upper end connected by suitable coupling means 37 to the upper portion of the corresponding end radiator section.

While one end of the tube 28 has swiveled connection with the bushing 27 it has its opposite end screw threaded so that the oppo-

site bushing 25 may be screwed on to the adjacent end of said tube 28 and the bushing 25 then screwed into the screw threaded opening 23 of the corresponding end radiator section. By virtue of this connection between the tube and said bushings, the tube is supported in the conduit at the lower portion of the radiator. 70

The tube 28 incloses the heating means and, as shown particularly in Figs. 6 and 9, 75 there is shown a Lavite or other suitable non-conducting core 38 for the support of the multiple series circuits 39 and 39'. This insulating core 38 is shown as formed of one piece but it is obvious that it may be formed 80 in sections arranged end to end, and this sectional arrangement it is thought entirely unnecessary to illustrate. Whether the core be formed in one piece or in sections, it is supported on a suitable metallic rod 40 85 which fits snugly within the core and which has its ends projecting beyond the ends of the core and reduced, as indicated at 41 and 42. The core is held against lateral displacement on the rod 40 by collars 43 and 45. The metallic collar 43 is screwed on to the reduced end 42 of the rod and the collar 45 which is preferably of insulating material is screwed on to the reduced end 41 of the rod, engaging the annular internal shoulder 95 50 of the bushing 25. The metallic collar 43 and the corresponding end of the rod 40 are preferably spaced slightly from the plug 29 of the tube 28 to provide an insulating space *a* between the plug 29 and the collar 43 and 100 the rod 40. This insulating space *a* permits of slight expansion of the supporting rod in the core without danger of breaking the latter. Both of said collars fit normally snugly against the respective ends of the 105 core.

The insulating collar 45 is provided with a plurality of sockets arranged substantially concentrically with relation to the supporting rod 40 and which are adapted 110 to take the interiorly screw threaded metallic sleeves 46 into which are screwed the inner ends of the terminal rods 47, 48 and 49 which project outwardly through the bushing 25. The terminal 47 is connected 115 by a plate 51 with the adjacent reduced end 41 of the supporting member 40 by means of a suitable fastening 52, as shown.

The insulating collar 45 is relatively large in diameter to allow for the required space 120 between the terminals 47, 48 and 49 and the supporting rod 40 so as to prevent or lessen the chances for short circuiting.

The bushing 25 has its outer face provided with a plurality of screw threaded 125 sockets 53 adapted to take suitable screw threaded fastenings 54 designed to secure the metallic cap 55 against the outer face of the bushing 25 and which cap is provided with an internal annular shoulder 56. 130

A fiber bushing 57 is supported by said metallic cap 55. This may be accomplished by providing the inner end of the fiber bushing 57 with a radial annular flange 59 5 adapted to engage the internal annular shoulder 56 of the cap 55. This fiber bushing 57 carries metallic sleeves 60 through which the aforesaid terminals 47, 48 and 49 project. The inner ends of these sleeves 10 60 engage the burs 61 mounted on said terminals 47, 48 and 49 in the cooling space 62 between the insulating collar 45 and the fiber bushing 57 and by means of burs 67 the fiber bushing 57 and sleeves 60 are held 15 in close engagement with burs 61. The cooling space 62 prevents direct contact of the fiber bushing 57 with the heating element.

The outer end of the fiber bushing 57 is 20 reduced to form an annular shoulder 63 to receive the fiber cap 64 which may be secured on said shoulder by means of suitable fastenings 65. These fastenings 65 preferably have screw threaded connection with 25 the fiber bushing 57 and the cap 64 provides a space 66 for the outer ends of the terminals 47, 48 and 49. The outer ends of the terminals 47, 48 and 49 are screw threaded to receive the binding burs 67 and 30 the fiber cap 64 has an outlet 68 for the passage of the wires or combined insulating cord which may lead from a suitable source of supply (not shown). The removal of this outer cap 64 exposes the terminals to 35 easy access in connecting the wires from the source of supply and the extended terminals with fiber coverings provide for good insulation of the wires beyond the end of the tube and the inclosing cap which 40 renders the same less subject to injury by close contact to direct heat of the coil.

The core 38 may be heated by various arrangements. One way is to provide for a double threaded winding resistance multiple 45 series or three heat combination in such form that the single, double or quadruple heat to which the core is subjected is uniformly distributed from end to end of the core and the inclosing tube, thus heating 50 the water uniformly in each and every section of the radiator. To these ends the core may have an external double thread to form the spiral grooves 69 and 70, the former to receive the wire 71 and the latter 55 to take the wire 72. The wires 71 and 72 are connected at one of their ends to the metallic collar 43 by the terminals 44 and 44', respectively, with their opposite ends connected to the terminals 48 and 49, respectively, by the binding nuts 73 and 74, 60 respectively. The collar 43, being connected to the core supporting rod 40, there is thus effected an intersecting of the complete winding in the middle at one end of the core.

65 The core supporting rod 40 forms a sup-

port for the core and also acts as a return conductor in the double or quadruple heats. It will be understood that the core on which the resistance wires are wound need not necessarily be grooved, as stated, but may be smooth and wire ribbon or round wire used. In any event, the winding should be 70 equally interspaced and interwound between each other after the fashion of the double thread principle. Whether the core be 75 smooth or grooved after the winding of the resistances thereon or in the grooves, the intervening space between the core and the walls of the inclosing tube 28 may be filled, if desired, by any suitable non-conducting 80 material, as shown in Fig. 6, and the filling material and the core made integral so as to exclude all air from this space which would normally remain between the core of Fig. 9 and the tube 28.

In Fig. 14 is shown a bushing 27' adapted to be substituted for the bushing 27, if desired, and which is adapted to have swiveled connection with one end of the tube 28. This modified form of bushing 27' has neither the outlet 32 nor the passages 30 of the bushing 27, but is in the form of a smooth bore chambered bushing without ports.

From the foregoing it will be understood 90 that the current may under certain conditions pass into the core through one resistance and out through the other; that under other conditions the current may pass through one resistance and return through the supporting rod 40; and that under other 95 conditions the current may pass into the core through both resistances with the supporting rod 40 acting as a common return for both resistances whereby I provide for a single, double or quadruple heat application uniformly distributed.

This case in part embraces portions of the subject matter of my application for electric radiators filed August 21, 1913, Serial No. 785,970.

110 What is claimed is:

1. A heating element for radiators comprising a hollow core of non-conducting material, a supporting rod for said core fitted closely therein and at its ends projecting beyond the ends of the core with the projecting ends reduced and screw threaded, a metallic collar secured on one of the reduced screw threaded ends of the rod and engaging the corresponding end of the core, an insulating collar engaging the opposite reduced screw threaded end of the rod and engaging the corresponding end of the core, resistance wire terminals connected to both of said collars, a metallic connection between said rod and one of the terminals of one of said collars, a double threaded winding resistance connection between the terminals of said collars, and a casing for said core.

2. A heating element for radiators com-

130

prising a hollow core of non-conducting material, a supporting rod for the core, a metallic collar secured to one end of the rod and engaging the corresponding end of the core, an insulating collar engaging the opposite end of the rod and engaging the corresponding end of the core, resistance wire terminals connected to both of the collars, a metallic connection between said rod and 10 one of the terminals of the insulating collar, a double threaded winding resistance connection between the terminals of said collars, and a casing for the core.

3. A heating element for radiators comprising a hollow core of non-conducting material, a supporting rod for the core, a metallic collar secured to one end of the rod and

engaging the corresponding end of the core, an insulating collar secured to the other end of the rod and engaging the corresponding 20 end of the core, resistance wire terminals connected to both of said collars, a double threaded winding resistance connection between the terminals of said collars, and means connecting the intermediate terminal 25 of the insulating collar with said rod whereby the rod may form the return for one of said resistances or the return common to both of said resistances.

In testimony whereof I affix my signature 30 in presence of a witness.

WILL R. SAVAGE.

Witness:

D. O. BARNELL.
